UNITED STATES PATENT OFFICE.

THOMAS MADGETT, OF BUFFALO, NEW YORK.

IMPROVED BOOT-CRIMPING DEVICE.

Specification forming part of Letters Patent No. 40,634, dated November 17, 1863.

To all whom it may concern:

Be it known that I, THOMAS MADGETT, of Buffalo, in the county of Erie and State of New York, have invented a new and Improved Boot-Crimping Device; and I do hereby declare that the following is a full, clear, and exact description of the same, reference being had to the accompanying drawings, making a part of this specification, in which—

Figure 1 is a side view of my invention; Fig. 2, a plan or top view of the same.

Similar letters of reference indicate corresponding parts in the two figures.

This invention relates to an improvement on the single lever boot-crimping machine, which consists of fixed pressure-plates and a movable crimping-plate.

My invention consists in arranging the pressure-plates and the crimping-plate in such a manner that both may be moved simultaneously in opposite directions, whereby it is believed that a more efficient device is obtained for the purpose than those previously devised.

A represents a frame, which may be of cast-iron and secured permanently to any proper fixture. This frame is composed of a horizontal plate, *a*, supported at its ends by standards *b b* of any suitable form. To one of the standards *b* there is connected, by a hinge, *c*, a bar, *B*, having two upright plates, *C C'*, connected to it by bolts *d*, which pass through oblong slots *e* in the bar *B*, and admit of a lateral adjustment of said plates toward and from each other, said adjustment being accomplished by means of a screw, *D*. This arrangement is peculiarly similar to many of the ordinary crimping-machines in use, except the bar *B*, which in the old machines is fixed.

E represents a crimping-plate, which may be of the usual form and provided with the usual clamp and screw, *F*, for drawing and se-

curing the boot-front (represented by dotted lines in Fig. 1) on the crimping-plate *E*. This crimping-plate is connected at one end to the standard *b* by a joint, *f*, and the opposite end is connected by a link, *g*, to a lever, *G*, which has its fulcrum *h* on the top of the standard *b'*, the link *g* being connected to the outer end of the lever *G*, and the inner end of the latter being underneath the free or disengaged end of the bar *B*, as shown clearly in Fig. 1. The lever *G* may have a socket, *i*, at its outer part to receive a bar or handle, *j*, to afford additional leverage-power.

From the above description it will be seen that when the bar or handle *j* is lowered the bar *B*, and consequently the plates *C C'*, will be raised by the action of the inner end of the lever *G* against the free end of bar *B*, and the plate *E* lowered by the action of the link *g*, and the boot-front will consequently be forced and pressed between the plates *C C'*, which are adjusted so as to press sufficiently hard against the boot-front and effectually crimp and smooth the same on the plate *E*. By this arrangement the crimping will be accomplished far more expeditiously than by the ordinary machine, in which the crimping-plate *E* is only moved.

I do not claim the pressure-plates *C C'*, nor the crimping-plate *E*, for they are in common use; but

I do claim as new and desire to secure by Letters Patent—

The crimping-plate *E*, in combination with the pressure-plates *C C'*, attached to the hinged bar *B*, the above parts being arranged with the lever *G* and link *g*, or their equivalent, to operate as and for the purpose herein set forth.

THOMAS MADGETT.
